(73) Assignee: **The Boeing Company**, Seattle, WA (US)

(57) **CLAIM**

The ornamental design for a blended wing and multiple-body airplane configuration, as shown and described.

DESCRIPTION

FIG. 1 is a top, front isometric view of the aircraft, with the broken line showing for illustrative purposes and forming no part of the claimed design;

FIG. 2 is a top plan view of the aircraft;

FIG. 3 is a bottom plan view of the aircraft;

FIG. 4 is a left side elevation view of the aircraft;

FIG. 5 is a right side elevation view of the aircraft;

FIG. 6 is a front elevation view of the aircraft; and,

FIG. 7 is a rear elevation view of the aircraft.
